HAND PROTECTING DEVICE

William J. McCann, Lakewood, Ohio

Application April 20, 1932, Serial No. 606,419

8 Claims. (Cl. 2—20)

This invention relates to improvements in hand protecting devices such as are used, for example, by housewives in grasping the heated handles of cooking utensils and the like.

5 The general object of the present invention is the provision of an improved hand protecting device of the character described, which device is simple and inexpensive in construction, convenient to use, neat and pleasing appearance and 10 of great durability.

A more specific object of the present invention is the provision of a hand protecting device of the character described which comprises an elongated gripping portion of preformed inverted U-shape in cross section and a pair of elongated protecting side shield portions, one on each side of said gripping portion. The front ends of said side shield portions are connected, preferably by a 15 detachable connection, to the opposite sides of the front end of said gripping portion, whereby an elongated thumb or finger receiving cavity is formed along each side of said gripping portion. Inasmuch as the rear ends of said side shield portions are free of connection to said gripping 20 portion, convenient access to said cavities is readily afforded.

25 A further object of the present invention is the provision of an improved hand protecting device of the character described, said device, in its preferred embodiment, having its gripping portion maintained in inverted U-shape in cross section by means of an elongated "backbone" member of corresponding shape in cross section, said member being removably secured in an elongated pocket 30 with which said gripping portion is provided. Means is preferably provided for preventing accidental escape of said "backbone" member, but the removal of said member, when desired, such as when the device is laundered, can be readily 35 effected.

40 A further object of the present invention is the provision of a hand protecting device of the character described having simple and inexpensively formed means for enabling the device to be readily hung upon a hook, nail or the like, in such position that it may be easily and conveniently grasped when its use is desired.

45 Further objects of the present invention are in part obvious and in part will appear more in detail 50 hereinafter.

The invention will be readily understood from the following description thereof, reference being had to the accompanying drawing in which:

55 Fig. 1 is a top plan view of one form of the present device, the view showing said device in

its opened out condition; Fig. 2 is a similar view of said device in its condition for use; Fig. 3 is a cross sectional view of said device in its condition for use, the view being on the line 3—3, Fig. 2; Fig. 4 is a similar view of said device in its opened out condition, the view being on the line 4—4, Fig. 1; Fig. 5 is a top plan view of a slightly modified form of the present device, the view showing said device in its opened out condition; and Fig. 6 is a side elevation of said modified form of the present device.

60 Referring first to the form of the device shown in Figs. 1 to 4 inclusive, it will be seen that said device, in plan view, is of generally rectangular shape when in its opened out condition. Preferably, said device comprises a lower layer of fabric 1, an upper layer of fabric 2 and suitable padding 3 therebetween, said padding being of cotton batting, shaker flannel or other suitable material of such character and/or of such thickness as to be heat resisting to a greater or lesser degree. The front and rear edges 5 and 6, respectively, and the side edges 7 of the present device are suitably bound by cloth tape 9 or the like, secured to said layers and said padding by suitable stitching 10. Preferably, and as shown, the upper and lower layers 1 and 2 are connected by suitable stitching 11, so that the device is of generally quilt construction, as will be readily understood.

65 Secured to the upper fabric layer 2, at substantially the middle thereof and extending from substantially the front edge 5 to substantially the rear edge 6, is a cloth strip 12; the side edges 13 of which are preferably stitched at 14 or otherwise suitably secured to said upper fabric layer. The front edge 16 of said strip is also secured to said upper fabric layer, preferably by the stitching 10 which secures the binding tape 9 in place. The strip 12 is so secured to said upper fabric layer 2 that some transverse fullness is provided, 70 whereby a pocket 18 is formed between said strip and said upper layer. This pocket is adapted to removably receive an elongated "backbone" member 20 of preformed U-shape in cross section, said member being of rubber, felt composition or other suitable material that can be given the 75 preformed shape just mentioned. The length of said "backbone" member is slightly less than that of the pocket 18 and in order to prevent accidental escape of said member from said pocket, 80 the mouth of said pocket is preferably restricted, such as by the stitching 22. Therefore, in order to insert the "backbone" member 20 into the pocket 18, and also, to remove it therefrom, the 85 transverse arching or curvature of said member

90

95

100

105

110

must be slightly increased, as will be readily understood.

The transverse middle section of the present device constitutes the gripping portion thereof, 5 and due to the transversely arched shape of the "backbone" member 20, which member forms a part of the top of said gripping portion, said gripping portion top has a corresponding transverse arch or curvature, a preformed shape which 10 it retains.

The two sections of the present device lying alongside the strip 12, on opposite sides thereof, constitute the side walls 25 of the gripping portion and when the device is in its condition for 15 use, as in Fig. 2, for example, said gripping portion side walls are more or less vertically disposed, thereby giving the entire gripping portion an inverted U-shape in cross section, as best shown in Fig. 3.

The two side marginal sections of the present device constitute the protecting side shield portions 28 thereof. These side shield portions, particularly the front end parts thereof, are adapted to extend more or less vertically when the present device is in its condition for use, as in Fig. 20 2, for example. Therefore, when the device is in such condition, an elongated cavity 32 is formed along each side of the gripping portion, each of said cavities having for its inner side a side wall 25 of the gripping portion and having for its 25 outer side a side shield portion 28. One of the cavities 32 is for a thumb of the hand of the person using the device and the other of said cavities for the fingers of said hand, as will be 30 readily understood.

Fig. 1 of the accompanying drawing shows the above described form of the present device in its opened out condition. In such condition, it is substantially flat, the middle part of the gripping portion thereof having a slight upward curvature in cross section because of its correspondingly curved "backbone" member 20. Therefore, during quantity shipment or storage, the present devices should preferably remain 45 in their opened out condition, inasmuch as maximum compactness is obtained thereby.

In order to enable the present device to be arranged in its condition for use, as in Fig. 2, for example, means is provided for effecting connection of the front end of each of the side shield portions 28 to the front end of the adjacent side wall 25 of the gripping portion. Such connection is preferably of detachable character, in order to enable the present device to be readily 50 changed from its opened out condition to its condition for use, and vice versa. In the form of the device shown in Figs. 1 to 4 inclusive, detachable connection of the side shield portions 28 to the side walls 25 of the gripping portion is effected by snap fasteners, the front ends of said side shield portions being each provided with a stud member 35 and the front end of each of said gripping portion side walls being provided with a cooperating socket member 36. In this form 55 of the present device, the connecting members 35, 36 are arranged in substantially a straight line along the front edge 5 thereof, the stud members 35 being located adjacent the side edges 7 and the socket members 36 being located adjacent the strip 12.

The rear ends of the side shield portions 28, being free of connection to the gripping portion, lie in spaced relation thereto, as clearly shown in Fig. 2. Convenient access to the cavities 32 is therefore always afforded and proper gripping

of the present device in position for use, is as a result easily and conveniently accomplished.

In order to enable the present device to be quickly and easily hung upon a hook, nail or the like, the rear end of the "backbone" member 20 is provided with a longitudinally disposed extension in the form of an ear 40, said ear being provided with an aperture 41 of such size as to conveniently receive a hook, nail or the like. In such suspended position, the present device is 85 always available for use.

The form of the present device illustrated in Figs. 5 and 6 of the accompanying drawing differs but slightly from the foregoing described form of the device illustrated in Figs. 1 to 4 inclusive of said drawing. In the modified form of Figs. 5 and 6, buttons 36a and cooperating button holes 35a are used to detachably connect the protecting side shield portions 28a to the side walls 25a of the gripping portion, rather than snap fasteners as in said previously described form. Furthermore, in said modified form, the fastening means of the side shield portions 28a, that is, the button holes 35a in the embodiment illustrated, are not in a straight line with their cooperating fastening means, to wit, the buttons 36a, but are offset rearwardly therefrom. The result of such rearward offsetting is the raising of the rear ends of the side shield portions 28a, as shown in Fig. 6 and as will be readily understood.

Preferably, and as shown, in the modified form of the device illustrated in Figs. 5 and 6, the front edges 5a of the side shield portions 28a are inclined slightly rearwardly relative to the front edge 5b of the gripping portion. This causes the 100 button holes 35a to be located adjacent said front edges 5a, rather than rearwardly therefrom.

Although in each of the two here illustrated forms of the present device I have shown a gripping portion which is maintained in an inverted 115 U-shape in cross section by a correspondingly shaped "backbone" member, and in the preferred forms of my invention I prefer to use such a member, it is to be understood that other means may be employed to maintain the gripping portion in 120 such a preformed shape. For example, the parts forming the gripping portion, namely, those portions of the lower and upper fabric layers 1 and 2 and the padding 3 therebetween, may be so stitched together as to give them such a preformed shape. Likewise, other changes may be made in the present device without departing from either the scope or the spirit of this invention.

As will be readily understood, the construction 130 of the side walls of the gripping portion and the side shield portions is such, due partly to the "quilt-like" stitching 11, that said portions have sufficient rigidity to more or less hold their positions but ample flexibility to enable a heated 135 cooking utensil handle to be easily and firmly grasped.

What I claim is:

1. A hand protecting device of the character described, comprising an elongated gripping portion, and a pair of elongated protecting side shield portions, one on each side of said gripping portion, the front end part of each of said shield portions being detachably connected to the front end part of said gripping portion and the rear end parts of said shield portions being free of connection to said gripping portion.

2. A hand protecting device of the character described, comprising an elongated flexible gripping portion, a pair of elongated flexible protect-

ing side shield portions, one on each side of said gripping portion, the front end part of each of said shield portions being connected to the front end part of said gripping portion and the rear end parts of said shield portions being free of connection to said gripping portion, and removable means for giving said gripping portion a preformed inverted U-shape.

3. A hand protecting device of the character described, comprising an elongated flexible gripping portion having an elongated pocket, a pair of elongated flexible protecting side shield portions, one on each side of said gripping portion, the front end part of each of said shield portions being connected to the front end part of said gripping portion, the front end part of each of said shield portions being connected to the front end part of said gripping portion and the rear end parts of said shield portions being free of connection to said gripping portion, and removable means in the pocket of said gripping portion for giving said portion a preformed inverted U-shape.

4. A hand protecting device of the character described, comprising an elongated flexible gripping portion having an elongated pocket, a pair of elongated flexible protecting side shield portions, one on each side of said gripping portion, the front end part of each of said shield portions being connected to the front end part of said gripping portion, the front end part of each of said shield portions being connected to the front end part of said gripping portion and the rear end parts of said shield portions being free of connection to said gripping portion, an elongated member of preformed inverted U-shape arranged in the pocket of said gripping portion for giving said portion a corresponding preformed inverted U-shape, and means for preventing accidental escape of said member from said pocket.

5. A hand protecting device of the character described, comprising an elongated flexible gripping portion having an elongated pocket, a pair of elongated flexible protecting side shield portions, one on each side of said gripping portion, the front end part of each of said shield portions being connected to the front end part of said gripping portion, the front end part of each of said shield portions being connected to the front end part of said gripping portion and the rear end parts of said shield portions being free of connection to said gripping portion, and an elongated member of preformed inverted U-shape arranged in the pocket of said gripping portion

for giving said portion a corresponding preformed inverted U-shape, said elongated member being provided at one end with an extension having an aperture therein for enabling the device to be hung upon a hook or the like.

6. A hand protecting device of the character described, comprising a generally rectangular flexible structure, the side portions of which constitute protecting shield portions and the middle portion of which constitutes a gripping portion, said gripping portion being provided with a pocket arranged at substantially the middle of said structure and extending from the front end thereof to the rear end thereof, a member of preformed inverted U-shape in cross section arranged in said pocket and having a length corresponding to that of said pocket, whereby said gripping portion is given by said member a corresponding preformed inverted U-shape, and means for connecting the outer front corners of said shield portions to said gripping portion adjacent the front end thereof, whereby an elongated pocket is formed along each side of said gripping portion.

7. A hand protecting device of the character described, comprising an elongated gripping portion and a pair of elongated protecting side shield portions, one on each side of said gripping portion, and means for detachably connecting the front ends of said shield portions to the front end of said gripping portion, said means comprising fastening parts on the front ends of said shield portions and cooperating fastening parts on the front end of said gripping portion, the fastening parts on the front ends of said side shield portions being offset rearwardly from the fastening parts on said gripping portion when said side shield portions are free of connection to said gripping portions.

8. A hand protecting device of the character described, comprising an elongated gripping portion, a pair of elongated protecting side shield portions, one on each side of said gripping portion, and means for detachably connecting the front ends of said shield portions to the front end of said gripping portion, said means comprising fastening parts on the front ends of said shield portions and cooperating fastening parts on the front end of said gripping portion, the front edges of said shield portions being inclined rearwardly relative to the front edge of said gripping portion when said shield portions are free of connection to said gripping portion.
